UNITED STATES PATENT OFFICE

BENJAMIN CHERRY, OF PHILADELPHIA, PENNSYLVANIA

PICTURE-PACKET-DISPLAY DEVICE

Application filed August 21, 1928. Serial No. 300,978.

The object of this invention is to produce a new and improved advertising and display card whereby a plurality of scenes or slogans may be successively displayed at a common 5 point.

This invention contemplates the production of a picture card and display novelty primarily adapted for use as a souvenir and of special interest to children.

10 Display novelties in the form of souvenir post-cards or packets have long been known. These generally are in the form of a long string of pictures joined successively at their margins. The pictures as displayed must, 15 therefore, be seen in a certain fixed sequence. The only way to see any one picture or device displayed is to pass by those which precede it.

It is one of the objects of this invention to arrange a group of pictures or other objects to 20 be displayed so that they may be seen in any sequence desired without the necessity of previously passing by those which precede it.

Another object of this invention is to arrange a group of pictures so that they may be 25 successively seen at a common point.

Another object of this invention is to so arrange a group of pictures, slogans, or other objects to be displayed so that they may be successively brought into the line of vision 30 at a common point and give the visual impression of moving pictures.

These and other objects of the invention will become apparent from the following detailed description and accompanying drawings.

Figure 1 discloses the packet entirely open with one of the pictures displayed at the common point.

Figure 2 is a section taken along the line 40 2-2 of Figure 1.

Figure 3 is a top view of the screen through which the pictures or slogans are displayed.

Figure 4 is a top view of an assembly of 45 pictures or slogans before they are mounted on the screen for display.

Figure 5 is a top view of the folded packet.

Figure 6 is a view along the line 6-6 of the Figure 5.

Referring more specifically to the drawings, 50 1 represents the new device as assembled

consisting of a transparent screen 2 and a plurality of pictures arranged around it and attached thereto at the points 3.

The screen may be of glass, mica, celluloid and any other transparent substance.

The objects to be displayed may be formed of a single piece of cardboard 5 as shown in Figure 4, having a hole 6 which is filled by the transparent screen 2 and margins 7 to

which the transparent screen is attached, and wings 8 to which are attached the pictures or display devices 3. A scored line 7 permits the pictures or display devices to be moved into and out of operative relation with the screen 2 without breaking the cardboard on

which the picture is mounted. The display devices may be mounted on one or both sides of the cardboard as desired. If the pictures 60 3 are mounted only on one side, then one display unit can be attached on the upper face of the display device and one on the lower face as shown in Figure 2.

It is one of the objects of this invention to arrange a group of pictures or other objects to 65 be displayed so that they may be seen in any sequence desired without the necessity of previously passing by those which precede it.

Another object of this invention is to arrange a group of pictures so that they may be 70 successively seen at a common point.

Another object of this invention is to so arrange a group of pictures, slogans, or other objects to be displayed so that they may be successively brought into the line of vision 75 at a common point and give the visual impression of moving pictures.

These and other objects of the invention will become apparent from the following detailed description and accompanying drawings.

Figure 1 discloses the packet entirely open with one of the pictures displayed at the common point.

Figure 2 is a section taken along the line 40 2-2 of Figure 1.

Figure 3 is a top view of the screen through which the pictures or slogans are displayed.

Figure 4 is a top view of an assembly of 45 pictures or slogans before they are mounted on the screen for display.

Figure 5 is a top view of the folded packet.

Figure 6 is a view along the line 6-6 of the Figure 5.

Referring more specifically to the drawings, 50 1 represents the new device as assembled

consisting of a transparent screen 2 and a plurality of pictures arranged around it and attached thereto at the points 3.

The screen may be of glass, mica, celluloid and any other transparent substance.

The objects to be displayed may be formed of a single piece of cardboard 5 as shown in Figure 4, having a hole 6 which is filled by the transparent screen 2 and margins 7 to

which the transparent screen is attached, and wings 8 to which are attached the pictures or display devices 3. A scored line 7 permits the pictures or display devices to be moved into and out of operative relation with the screen 2 without breaking the cardboard on

which the picture is mounted. The display devices may be mounted on one or both sides of the cardboard as desired. If the pictures 60 3 are mounted only on one side, then one display unit can be attached on the upper face of the display device and one on the lower face as shown in Figure 2.

It is one of the objects of this invention to arrange a group of pictures or other objects to 65 be displayed so that they may be seen in any sequence desired without the necessity of previously passing by those which precede it.

Another object of this invention is to arrange a group of pictures so that they may be 70 successively seen at a common point.

Another object of this invention is to so arrange a group of pictures, slogans, or other objects to be displayed so that they may be successively brought into the line of vision 75 at a common point and give the visual impression of moving pictures.

These and other objects of the invention will become apparent from the following detailed description and accompanying drawings.

Figure 1 discloses the packet entirely open with one of the pictures displayed at the common point.

Figure 2 is a section taken along the line 40 2-2 of Figure 1.

Figure 3 is a top view of the screen through which the pictures or slogans are displayed.

Figure 4 is a top view of an assembly of 45 pictures or slogans before they are mounted on the screen for display.

Figure 5 is a top view of the folded packet.

Figure 6 is a view along the line 6-6 of the Figure 5.

Referring more specifically to the drawings, 50 1 represents the new device as assembled

around the perimeter of the same; a plurality of display devices movably attached to the lower face of the said screen at a plural number of points around the perimeter of the same, any one of the display devices in the said upper and lower portions being adapted to be selectively brought into registry with the said screen.

2. A display device consisting of a polygonal transparent screen having an upper and lower face; a plurality of display devices movably attached to the upper face of the said transparent screen at the different edges of the said polygon; a plurality of display devices movably attached to the lower face of the said screen at the different edges of the said polygon, any one of the display devices in the said upper and lower portions being adapted to be selectively brought into registry with the said screen.

3. A display device consisting of a rectangular transparent screen having an upper and a lower face; a plurality of display devices hingedly attached to the upper face of the said transparent screen at the different edges of the said rectangle; a plurality of display devices rotatably attached to the lower face of the said transparent screen at the different edges of the said rectangle, any one of the display devices in the said upper and lower portions being adapted to be selectively brought into registry with the said screen.

4. A display device consisting of a rectangular transparent screen having an upper and lower face; a rectangular mat attached to the upper face of the said transparent screen; a rectangular mat attached to the lower face of the said screen; a display device hingedly attached to each of the edges of the upper and lower mats, any one of the said display devices being adapted to be selectively brought into registry with the said screen.

5. In witness whereof I hereby affix my signature.

BENJAMIN CHERRY.
